DESIGN FOR A FLOWER HOLDER

William J. Keller, St. Louis, Mo.

Application October 28, 1936, Serial No. 65,555

Term of patent 14 years

To all whom it may concern:

Be it known that I, William J. Keller, a citizen of the United States, residing in the city of St. Louis and State of Missouri, have invented a new, original, and ornamental Design for a Flower Holder, of which the following is a specification, reference being had to the accompanying drawing, forming part thereof.

Fig. 1 is a side elevation of a flower holder showing my new design.

Fig. 2 is a top plan view of the holder.

I claim:

The ornamental design for a flower holder, as shown.

WILLIAM J. KELLER.
